UNITED STATES PATENT OFFICE.

VLADIMIR V. MESSE, OF WAUWATOSA, WISCONSIN.

DEVICE FOR RAISING SUNKEN VESSELS.

1,288,108.

Specification of Letters Patent.

Patented Dec. 17, 1918.

Application filed June 25, 1918. Serial No. 241,777.

To all whom it may concern:

Be it known that I, VLADIMIR V. MESSE, a citizen of the United States, residing in Wauwatosa, in the county of Milwaukee and 5 State of Wisconsin, have invented certain new and useful Improvements in Devices for Raising Sunken Vessels, of which the following is a specification.

The present invention relates to a device 10 for raising sunken ships, and has for its object to provide a device of this character which embodies novel features of construction whereby the available power can be utilized in a most effective manner for hoisting 15 a sunken vessel from the bottom of the sea.

Further objects of the invention are to provide a device of this character which can be towed from place to place without difficulty, which is easily operated and has a very powerful lifting force, and which can be quickly brought into operative position and connected to the sunken vessel which it is desired to raise.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawings, in which:—

Figure 1 is a perspective view of a device for raising sunken vessels constructed in accordance with the present invention.

Fig. 2 is a longitudinal vertical sectional view through the rotatable hollow float.

Fig. 3 is a transverse sectional view through the same on the line 3—3 of Fig. 1.

Fig. 4 is an enlarged sectional view through one of the pumps, the cut off valve being shown by full lines in an open position and by dotted lines in a closed position.

Fig. 5 is a detail sectional view on an enlarged scale through one of the hydraulic compensators.

Corresponding and like parts are referred to in the following description and indicated in all the views of the drawings by the same reference characters.

Referring to the drawings, which illustrate one possible embodiment of the invention, the numeral 1 designates a hollow float

which is in the form of a cylindrical shell and rests upon the surface of the water with the main axis thereof in a horizontal position. This hollow float is water-tight and 60 has a tubular standard 2 arranged in an upright position at one end thereof, the upper end of the standard being open, while the lower end thereof is weighted or other means being provided to hold the standard in an 65 upright position. A hollow trunnion 3 projects laterally from one side of the standard 2 and extends centrally through the end of the float 1 into communication with the interior thereof. A ladder 4 is provided upon 70 both the exterior and interior of the standard 2, and in order to get into the interior of the hollow float 1 it is necessary for a person to descend into the tubular standard 2 from the top thereof and enter the float 75 through the hollow trunnion 3. A drive shaft 5 extends longitudinally through the hollow float 1, being journaled within suitable bearings at opposite ends thereof, and being connected to an electric motor 6 which 80 receives power from a generator upon the salvage boat 7. This boat may be an ordinary sea-going tug, and the electric wires 8 from the generator to the motor run from the top of the derrick 9 of the boat 7 to the 85 top of the tubular standard 2, extending into the tubular standard and having the extremities thereof connected to the motor. Provision is thus made for conveying current to the motor to drive the shaft 5. 90

Arranged within the interior of the hollow float 1 is a peripheral series of compartments 10 which are connected to each other by substantially Y-shaped passages 11, a suitable pump being provided in each 95 passage for producing a circulation of some fluid such as water through the several compartments. In the present instance this pump is formed by a pair of reversely acting propellers 12 which are arranged in the 100 branches of the Y-passages 11 and serve to draw the water through the arms of the passages and force it through the straight portions thereof, or vice versa. The two propellers 12 of each pump are rigid 105 with a transverse shaft 13 which extends through the arms of the Y-passage, being received within suitable packing boxes 14 and journaled within bearings 15 which combine both a radial and thrust ball bearing construction. One end of each of the 110 shafts is provided with a pulley 16 and the

several pulleys each have a rope drive 17 with the main drive shaft 5 which extends centrally through the float. It will thus be obvious that when the main shaft 5 is driven 5 all of the pumps will be simultaneously operated, and the arrangement of the pumps is such that they tend to produce a circulation of water or other fluid with which the compartments 10 are filled. There is 10 only enough of the water or fluid to partially fill the compartments 10, so that when the pumps are set in operation and the water started to circulate through the compartments, the center of gravity of the float 15 will be shifted while the center of buoyancy of the float remains at the geometrical center thereof. A moment of force is thus produced which tends to revolve the float about its longitudinal axis. The magnitude 20 of this turning moment is dependent upon the relative sizes of the water compartments and the size of the float itself, and by reversing the pumps the direction of rotation of the float can be reversed. The straight portion 25 of each of the Y-passages 11 is provided with a suitable cut-off such as the gate valve 18 so that the water can be prevented from flowing backward through the compartments if the motor becomes deranged or must be 30 stopped for any reason whatever. The exterior of the hollow float 1 is provided with a series of sets of differential spools, each set including a large spool 19 and a smaller spool 20, the larger spool 19 being secured 35 to the float by suitable means such as the Z strips 21. A hoisting cable 22 is operatively connected to the spools 19 and 20 of each set, said spools being shown as subdivided by ribs into helical channels which are 40 adapted to receive the hoisting cable 22 as it is wound upon and unwound therefrom. When the hollow float 1 is rotated in one direction the hoisting cables 22 are unwound from the large spools 19 and wound upon 45 the smaller spools 20, thereby producing a slack portion 22^a which constantly increases in size. The pulleys 23 of the grapple members engage the slack portions 22^a of the hoisting cables, and these pulleys, together with the grapple members A carried 50 thereby will be lowered when the float is rotated in the manner indicated above. After the grapple members have been lowered to the proper depth and properly engaged with the hull of the sunken vessel, the pumps 12 of the float are reversed and the direction of rotation of the float correspondingly reversed. The hoisting cables 22 are now wound upon the large spools 55 19 and unwound from the smaller spools 20, with the result that the slack portions 22^a of the cables are gradually taken up and the grapple members slowly raised. A very powerful hoisting force is thus brought 60 into play, the magnitude of the force de- 65

pending upon the difference in diameter between the large spools 19 and the smaller spools 20.

It is essential that the entire weight of the second boat be equally or nearly equally distributed between the several hoisting cables 22, and for this purpose each of the grapple members is provided with a hydraulic equalizer or compensator. These compensators each include a cylinder 24 which is filled 70 with some suitable fluid such as oil and has a piston 25 therein, said piston being connected to the upper end of the piston rod 26 which extends downwardly through a stuffing box 27 in the lower end of the cylinder. 75 The piston 26 is suitably packed at 28 to prevent the oil or fluid within the cylinder from leaking upwardly around the sides of the piston. The piston is provided with a central chamber 29 communicating with a 80 passage 30 opening through the bottom of the piston and also with a passage 31 opening through the top of the piston, communication between the latter passage and the chamber being controlled by a valve 32 85 which is normally held upon its seat by the action of a spring 33. The head 32^a of the valve is substantially in the form of a piston which is slidable within the chamber 29, so that when the pressure of the oil or fluid 90 within the chamber 29 reaches a certain point it will move the valve upwardly against the action of the spring 33 and open the passage 31, thereby permitting oil to circulate through the passages and chamber 100 105 from the lower portion of the cylinder 24 to the upper portion thereof. The degree of pressure necessary to permit this circulation of fluid depends upon the tension of the springs 33, and this can be regulated by adjusting the plugs 34 which are threaded in the piston 25 and against which the upper ends of the springs bear. The lower ends of the piston rods 26 are connected to the vessel to be raised, and it will be obvious that 110 if upon putting the device into operation one of the hoisting cables becomes taut while the other hoisting cables are still loose, all of the power will be exerted upon one of the grapple members, with the result that 115 the pressure upon the oil in the cylinder 24 of that particular grapple member will be sufficient to open the valve 32 and permit the oil to pass through the piston to the top thereof. The position of the piston within 120 the cylinder will thus be lowered and actual lifting of the sunken vessel delayed until all of the hoisting cables are taut and the power is substantially equally divided among the 125 grapple members. A continual rotation of the hollow float will then slowly take up the slack portions 22^a of the hoisting cables 20 and gradually bring the sunken vessel to the surface.

While I have illustrated and described one 130

preferable embodiment of the principles of my invention, I wish it understood that I do this by way of example only, not wishing to be restricted thereto as changes may be 5 resorted to without departing from the spirit and scope of my invention, as defined by the following claims.

Having thus described the invention, what I claim as new and desire to secure by Letters Patent, is:—

- 10 1. A device for raising sunken ships, including a hollow float, means for continuously circulating a fluid around the periphery of the float to rotate the float in the water, and hoisting means actuated by the rotation of the float.
- 15 2. A device for raising sunken ships, including a hollow float, a series of compartments extending around the periphery of the float, pumps for producing a continuous circulation of fluid through the compartments to rotate the float bodily in the water, and hoisting means actuated by the rotation of the float.
- 20 25 3. A device for raising sunken ships, including a hollow float, a peripheral series of compartments extending around the float, pumps between the several compartments, means for simultaneously actuating the 30 pumps to produce a continuous circulation of the fluid through the compartments and rotate the float bodily in the water, and hoisting means actuated by the rotation of the float.

4. A device for raising sunken ships, including a hollow float, a peripheral series of compartments extending around the float, pumps between the several compartments, a shaft extending longitudinally through the float, means for driving the shaft, an operative connection between the shaft and the pumps for simultaneously operating the same to produce a continuous circulation of fluid through the compartments to rotate the float bodily in the water, and hoisting means actuated by the rotation of the float.

5. A device for raising sunken ships, including a hollow float, a peripheral series of compartments extending around the float, circulation pipes connecting the compartments, pumps interposed in the circulation pipes, means for operating the pumps to produce a continuous flow of fluid through the compartments to rotate the float bodily upon the water, valves interposed in the circulation pipes to prevent backward movement of the fluid, and hoisting means actuated by the rotation of the float.

6. A device for raising sunken ships, including a hollow cylindrical float, means within the float for producing a continuous circulation of fluid around the periphery of the float to rotate the float in the water, differential spools upon the exterior of the float, and a hoisting cable having the ends thereof wound upon the differential spools.
